UNITED STATES PATENT OFFICE

2,011,205

DOMESTIC WATER BOILER

Ivan Turner, Richmond, England

Application September 7, 1934, Serial No. 743,142
In Great Britain March 15, 1934

8 Claims. (Cl. 126—132)

This invention relates to domestic water boilers for houses or apartments with self-contained hot water supply, and more particularly to coke-fired or like boilers which are employed for supplying hot water for baths, radiators and other domestic purposes, independently of cooking stoves; these "independent" boilers, as commonly fitted in kitchens or living rooms, are open to the objection that they do not provide the comfort of open fires, but on the other hand they may render the rooms unnecessarily warm when used to supply hot water during the summer months.

The main object of the present invention is to provide for the supply of hot water from the independent boiler, without inevitably heating the kitchen or other room in which the boiler is fitted, and for the separate or controlled heating of the room, without requiring a second fireplace recess and flues, the apparatus employed being adapted to take the place of the ordinary independent boiler.

According to this invention, I provide a hot water boiler of the independent type, that is independent of a cooking stove, with which boiler I combine an open fireplace having its framework combined with that of the boiler. In the back of the open fire place, which conveniently forms part of the boiler front and may slope forward from above the level of the burning fuel towards the top front of the boiler, I provide a hinged or detachable door or doors, giving access to the front bars of the boiler fire, so that these bars can be removed for cleaning or laying the boiler fire; normally the door or doors will be kept closed, so as to retain the heat, but they may be left open when the boiler fire is burning, if it be desired to warm the room when the open fireplace is not in use. The boiler firebox is fitted with a loose grid or bottom bars, which may be of the rocking or oscillating type for riddling the fire, with control means at the front of the open fireplace.

The invention is hereafter described with reference to the accompanying drawings, in which:

Fig. 1 is an elevation showing the open fireplace as seen from the front, parts being broken away.

Fig. 2 is a plan of the boiler, showing the flues in section.

Fig. 3 is a sectional elevation, taken at the center of Fig. 1.

Fig. 4 is a plan in section on the line 4—4 of Fig. 3, one half of each grate bottom being re-

moved and the ashpan of the open fireplace drawn forward.

Fig. 5 is a perspective view on a larger scale, showing the lower part of the open fireplace, with the ashpan and grate bottom lifted out.

Fig. 6 is a partial elevation in section, corresponding to Fig. 3, showing a modification.

The boiler *a*, which is shown as having water spaces at the vertical sides *a*¹ and at the back *a*², is arranged behind the open fireplace *b*, as clearly seen in Fig. 3. The sloping back of the open fireplace is arranged to form part of the boiler front *c*, which extends across the full width of the boiler and may support the back fire-brick *b*¹ of the open fireplace, the sloping part *c*¹ bulging forward above the level of this fire-brick and extending towards the top plate *d* of the boiler which overhangs the open fireplace. The side frames *e* (see Fig. 4), which support the fire-brick cheeks *b*² of the open fireplace, are tied together by a flanged plate *e*¹ secured by set-screws *e*²; these side frames *e* are arranged flush with the sides of the boiler so as to form extensions of the corresponding boiler walls, and their rear edges are shaped to fit against the sides of the boiler front *c*. The front frame *f* of the open fireplace extends up as far as the top plate *d* of the boiler, its transom *f*¹ supporting a hood or canopy *g* above the open fireplace. The frame members *e* *f* and the boiler front *c* are secured to the boiler by means of long horizontal studs *h* screwed into the boiler walls at the upper and lower front corners of the water spaces, with nuts *h*¹ fitted to the ends of these studs projecting through the frame *f*; the flanged plate *e*¹ is also secured to the boiler front *c* by bolts *e*³ at the back of the open fireplace.

In the sloping portion *c*¹ of the boiler front, there is provided a rectangular opening *c*² into which the front bars *i* of the boiler fire are fitted; these bars serve to retain the fuel heaped up on the boiler fire, it being customary to stoke boilers of this kind at long intervals, say every twelve hours. The bars *i* which may be separate or cast together, are accommodated inside the bulge in which the opening *c*² is formed and are held in place by notches *c*³ at the upper and lower ends of the opening, the bars being removable through the opening *c*² (after lifting the bars clear of the lower notches) for cleaning or laying the boiler fire. The opening *c*², which thus gives access to the boiler firebox, is adapted to be closed by a detachable door or doors *j* provided with hooks *j*¹ at the sides, these hooks engaging over

wedge-shaped lugs c^4 on the edges of the opening; a hole or holes j^2 may be provided on the front of the door to facilitate its removal and replacement.

5 The boiler is fitted with bottom fire-bars in the form of a loose grid k which rests upon lugs or ledges k^1 cast on the inner walls of the boiler a (see Figs. 3 and 4); beneath this grid, there is provided a transverse shaft l supported on two 10 brackets l^1 secured to the boiler front c , the shaft having two pairs of oppositely extending arms l^2 connected by transverse bars l^3 lying beneath the grid k towards its front and rear ends. A crank arm m dependent from the middle of the 15 shaft l is connected by a rod m^1 to a knob or handle m^2 at the front of the grate, so that the boiler fire can be shaken or riddled by oscillating the shaft l so as to rock the grid k .

20 The open fireplace b is shown as fitted with a removable grate bottom n having rear supports n^1 secured upon the flanged plate e^1 ; the front edge n^2 of the grate bottom is turned up to hold the fuel in place and it is supported for example on pegs f^2 projecting inwardly from the 25 frame f , the underside of the grate bottom being notched at f^3 to fit over these pegs so that it cannot slip forward accidentally.

25 In the bottom of the frame, and extending from front to rear under both fires, there is fitted a 30 large ashpan o , the front o^1 of which is provided with a handle o^2 and a suitable draft-regulator o^3 for controlling the admission of air to the boiler fire; the front o^1 may also be notched at o^4 for the passage of the rod m^1 which is guided 35 at this point by a hole or eye m^3 is a vertical rib e^4 below the front of the flanged plate e^1 . Above this ashpan and underneath the open fireplace, I provide a second ashpan p carried on the flanged plate e^1 which is of open hexagonal shape, as seen 40 in Fig. 5, the pan p normally covering this opening, so as to exclude all draft from above this pan into the boiler fire, and also from below this pan to the open fire, and the air for the latter being admitted through a regulating shutter p^1 in the 45 front p^2 of this second ashpan, which is fitted with a handle p^3 . The ashes collecting in the 50 second pan p can be tipped into the large bottom ashpan o by sliding the former outwards, as indicated in Fig. 4, and tilting it up, a scraper bar p^4 hinged at n^3 beneath the grate bottom n serving 55 to clear the pan as it is drawn out, and the ashes then falling through the open center of the plate e^1 into the bottom ashpan o .

55 The water spaces at the vertical sides a^1 of the boiler increase in width from the line where the sloping portion c^1 of the boiler front begins to bulge forward over the open fireplace b ; thus there is a relatively small firebox at the bottom 60 of the boiler, but from a few inches above the bottom bars k the combustion space widens out towards the front, as can be seen in Fig. 3, so that ample heating surface and fuel capacity are provided. An opening d^1 in the flat top plate d of the boiler allows fuel to be added after removal 65 of the lid d^2 , the smoke outlet q being located directly behind the firing hole d^1 . Suitable tapplings r r^1 r^2 for the flow, return and drain-off water pipes are provided, together with one or more manholes r^3 if desired.

70 The combustion gases from the open fire place b , which forms the front of the combined apparatus, escape from the top of the sloping back c^1 and beneath the boiler top plate d , which extends over the open fireplace, into horizontal flues s at the two sides of the boiler and thence 75

into a three-way junction fitting t , which also connects with the outlet q from the boiler fire. Separate dampers t^1 t^2 t^3 are provided for the three flues entering the fitting t , the two dampers for the side flues being connected together by a rod t^4 , and two separate control knobs or handles u u^1 for the two fires being arranged for operation from the front of the fireplace.

75 The front of the fireplace may be enclosed with a tiled or other panel v on each side, preferably detachable, so as to give the appearance of an ordinary open fireplace, as seen in Fig. 1, and at the same time to retain the heat radiated from the exterior of the boiler a ; the space above the boiler top plate d may then be closed in by extending the front frame f upwards above the canopy g and providing a hinged door w , which when opened (as shown in dotted lines in Fig. 3) allows the fuel to be fed to the boiler; a handle w^1 with a suitable catch w^2 enables the door to be 20 opened and closed, hinged door stays w^3 being provided if desired. If preferred, however, I may dispense with the door w , and leave the space above the boiler open as illustrated in Fig. 6, the top plate d of the boiler being in that case formed with a 25 suitable beading d^3 or the like. A guard fence may be placed round the sides and back of the firing hole d^1 , or this fence may be arranged at the edge of the top plate d , as indicated at x 30 in Fig. 3.

35 The boiler a and front frame f may rest upon a base y , at the front of which there is arranged a loose tray z to catch any cinders falling from the ashpans or from the open fireplace.

35 By this combination of an open fire place b with the hot water boiler a , I provide a highly adaptable boiler, which can be employed not only independently of the cooking stove, but either alone, with or without heating of the room by opening or closing the door j above the open fire place, or 40 in conjunction with the open fire when the room requires heating, or can be put out of operation, the heating of the room being then provided, if required by a fire in the open fire place b alone. Under normal conditions, the boiler will be maintained in operation for supplying hot water for 45 domestic purposes; the heating of the room will then be provided by the opening c^2 , part of the heat from the boiler combustion space being transmitted into the room. When heat from the 50 boiler combustion space is not needed to heat the room, the door j will be closed; similarly the door j will be closed when all of such heat is required to heat the water in the boiler, but in this 55 case a separate fire can also be provided in the open fire-place, if heating of the room is desired. Lastly if the boiler is out of operation, and it is required to warm the room without delay or for a short period, a fire can be lighted in the open 60 fire place alone. Both fires are preferably arranged to burn the same fuel, e. g. coke, and either or both may be provided with gas ignition means, as indicated at b^3 in Fig. 3, but it will be understood that either the boiler or the open fire place, or both, may be gas-fired, suitable supply 65 pipes and burners being provided as well known in the art.

What I claim is:—

70 1. A combined water boiler and open fire-place for domestic use, said boiler having side walls and a transverse wall partly common to said boiler and to said open fireplace, a combustion space within said boiler and bounded by said side and transverse walls, said open fire-place having other walls secured to said boiler 75

walls, and said partly common wall including an opening giving access from said open fire place to said combustion space, and means for closing said opening when all of the heat from said combustion space is needed to heat the water in said boiler.

5. 2. A combined water boiler and open fire place for domestic use, said boiler having a combustion space bounded by side walls and a sloping wall, 10 said sloping wall being partly common to said boiler and to said open fire place, said open fireplace having other walls secured to said boiler walls, and said sloping wall including an opening giving access from said open fire place to said combustion space, and a door for said opening, 15 said door being opened for passage of heat from said combustion space for the heating of the room in which said combined water boiler and open fire place is fitted.

20 3. A combined water boiler and open fire place, said boiler having inwardly facing walls and a wall partly common to said boiler and to said open fireplace, a combustion space within said boiler and having the front thereof bounded by said partly common wall, said partly common wall including an opening giving access from said open fireplace to said combustion space, bars across 25 said opening, and a door for said opening, said door being opened when heat from said combustion space is desired for the heating of the room.

25 4. A combined water boiler and open fire place, said boiler having vertical side walls connected transversely by a sloping wall partly common to said boiler and to said open fireplace, a combustion space within said boiler and bounded by said boiler walls, said sloping wall including an opening giving access from said open fireplace to said combustion space, detachable bars across said opening, and a door for said opening, said door being mounted on the side of said sloping wall remote from said combustion space, said door being opened when heat from said combustion space is desired for the heating of the room, and said detachable bars being removable from said opening in the open position of said door for free access to said combustion space.

30 5. A domestic heating appliance, comprising a water boiler having vertical side walls connected by a transverse wall and a combustion space bounded by said side walls and transverse wall, an open fireplace for heating the room in which said appliance is fitted, the back of said open fireplace being formed by said transverse wall and other walls of said open fireplace formed by extensions of the corresponding walls of said boiler,

said transverse wall having an opening giving access from said open fireplace to said combustion space, bars across said opening, and a door for said opening, said door being opened for the heating of the room from said combustion space, and said bars being removable from said opening in the open position of said door for free access to said combustion space from said fireplace.

5 6. A domestic heating appliance, comprising a water boiler having two opposite vertical side walls increasing in width upwardly and a sloping wall connected to the front edges of said vertical walls, said vertical side walls including water spaces, a combustion space within said boiler bounded by said vertical side walls and sloping wall, an open fireplace juxtaposed to said boiler, said sloping wall forming the back of said open fireplace and having an opening giving access from said open fireplace to said combustion space between said vertical side walls, and a door for 20 said opening, said door being closed when all of the heat from said combustion space is needed to heat the water in the boiler.

25 7. A domestic heating appliance, comprising a water boiler having two opposite vertical side walls connected by a transverse sloping wall, a combustion space within said boiler bounded by said vertical side walls and sloping wall, an open fireplace juxtaposed to said boiler, the back of said open fireplace being formed by said transverse wall and having an opening giving access from said open fireplace to said combustion space, an ashpan for said open fireplace, a lower ashpan for the firebox of said boiler, each of said ashpans supplying air to its own fire only, both said ashpans being operable from the front of said open fireplace, and said lower ashpan adapted to receive ashes dumped from the first of said ashpans.

30 8. A domestic heating appliance, comprising a water boiler having vertical side walls connected by a transverse wall, an open fireplace juxtaposed to said boiler, the back of said open fireplace being formed by the transverse wall of said boiler, a combustion space within said boiler and having the front thereof bounded by said transverse wall, independent flues for said boiler and open fireplace, said transverse wall having an opening for transmission of heat from said combustion space across said open fireplace during operation of said boiler, and a door for said opening said door being 40 closed when all the heat from said combustion space is needed for heating the water in said boiler.
